UNITED STATES PATENT OFFICE.

BENJAMIN F. FORSYTH, OF PAONIA, COLORADO, ASSIGNOR OF ONE-HALF TO BOY W. COPP, OF PAONIA, COLORADO.

LADDER.

1,031,110.

Specification of Letters Patent.

Patented July 2, 1912.

Application filed March 22, 1911. Serial No. 616,169.

To all whom it may concern:

Be it known that I, BENJAMIN F. FORSYTH, of Paonia, in the county of Delta and State of Colorado, have invented certain new and useful Improvements in Ladders; and I do hereby declare the following to be a full, clear, and exact description of the invention, such as will enable others skilled in the art to which it appertains to make and 10 use the same.

The object of my invention is to provide an improved, simple and highly efficient ladder which will permit of ready and easy climbing and at all times insure a secure 15 foot-hold for the user, it being unnecessary to disengage the feet from the foot-rests either in ascending or descending, the supporting means being constantly under control of the user.

20 The invention will be hereinafter fully set forth and particularly pointed out in the claims.

In the accompanying drawings, Figure 1 is a view in perspective of a ladder embodying my invention. Fig. 2 is an enlarged 25 longitudinal sectional view through one of the foot-rests. Fig. 3 shows a foot-rest detached.

Referring to the drawings, 1, 1, designate 30 two spaced apart uprights which are shown as mounted on a base 2 and provided at their upper ends with brackets for supporting the usual top step or shelf 3. The brackets are shown as forming bearings for the pintle of 35 a prop 4.

On each of the uprights I mount a foot-rest which is designed to be clamped and firmly held in place under the weight of the user but which may be released and caused 40 to assume a different position by the foot of the user, the two foot-rests being alternately manipulated. The means for so connecting each foot-rest to its respective upright as to enable them to be alternately slid upwardly 45 or downwardly may be widely varied. The means shown embodies, in addition to the foot-rest 5, an arm 6 secured to the underside of the foot-rest by any suitable means and projecting at its rear end through a slot 50 7 extending longitudinally in the upright. I have shown each arm 6 as secured to the uprights by pins 8 and 9 passed through openings in such arms on opposite sides of the uprights, the front pin 8 being on a

plane lower than the rear pin 9 so that the 55 weight of a foot-rest will cause the pins to bind against the front and rear faces of its upright to clutch the foot-rest thereon.

In order to prevent undue wear by the biting of the pins I employ plates 10 and 12 60 located between the pins and the faces of the uprights, the front plates 10 fitting in grooves 13 in the front face of the upright.

It will be understood that the two pins being on different planes at the front and rear 65 of each upright constitute clutches whereby the foot-rests are frictionally held locked to the uprights. I have shown springs 14 acting on the rear ends of arms 6 for holding the foot-rests as against accidental displacement when the foot is removed therefrom, the tension of the springs forcing the rear end of the arm 6 upwardly, causing the pins 70 to bind against the upright.

Each foot-rest 5 is provided with an adjustable loop 15 by pulling upwardly on which the foot-rest may be raised, the user placing his weight on one rest and elevating the other. Each foot-rest may be easily lowered by the operator pressing his foot on 80 a toe-plate 16 projecting upwardly from the inner end of the foot-rest, pressure thereon releasing the clutch and permitting ready lowering of the parts.

In practice, the operator by bearing his 85 weight upon one foot and lifting the other will, by engaging the loop 15 of the other foot-rest, so turn the latter as to release the clutch, and by pulling upwardly on the loop cause the foot-rest to assume either a higher 90 or the same plane as the other foot-rest. Then by transferring his weight to the foot-rest so moved into a different plane the other rest may, in like manner, be moved into either the same or a higher plane. To 95 lower the foot-rests the operator bears against the toe-plate 16, and allowing his weight to be wholly or partly placed on such foot-rest may move the latter downwardly the desired distance.

It will be observed that I have provided a ladder comprising but few parts and which will permit of easy and gradual ascension or descension, and one which will at all times insure a steady foot-hold.

I claim as my invention:

1. A ladder comprising spaced apart uprights having longitudinal slots therein,

109

105

- movable foot-rests on said uprights, arms on said foot-rests extending through said slots, and means carried by said arms for locking said foot-rests to said uprights.
5. 2. A ladder comprising spaced apart uprights having longitudinal slots therein, movable foot-rests on said uprights, arms on said foot rests extending through said slots, and means carried by said arms on opposite 10 sides of said uprights for locking said foot-rests to said uprights.
3. In a ladder, the combination with spaced apart uprights having longitudinal slots therein, of foot rests slidably mounted 15 thereon, arms carried by said foot-rests extending through the slots in said uprights, means carried by said arms for clutching said uprights to lock said foot-rests thereto,

and means carried by each foot rest for releasing it from its upright.

4. In a ladder, the combination with uprights, of foot rests slidably mounted thereon, each foot rest having a clutch for locking it to its upright, an adjustable loop secured to each foot rest, and a toe-plate 25 at the inner end of each foot-rest, the clutch being capable of being disengaged by the operator pulling upwardly on the loop or bearing on the toe-plate.

In testimony whereof, I have signed this 30 specification in the presence of two subscribing witnesses.

BENJAMIN F. FORSYTH.
